UNITED STATES PATENT OFFICE.

JAMES ANDREW GOODNER, OF ROCKY FORD, COLORADO.

PUMP.

Application filed January 6, 1927. Serial No. 159,398.

This invention aims to provide a simple form of rotary pump wherein leakage will be prevented, novel means being employed for supporting the rotor.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the accompanying drawings:—

20 Figure 1 shows in vertical section, a device constructed in accordance with the invention, parts being in elevation;

Figure 2 is a transverse section;

25 Figure 3 is a top plan wherein parts are broken away.

The device forming the subject matter of this application is a centrifugal pump, including a casing or stator. The casing or stator comprises a funnel-shape body 1 having a thickened base 12, into which is threaded a collar 6 having a flange 7 overlapping the upper surface of the base 12, the collar 6 carrying a spider 2 including a hub 8. The numeral 3 marks a bearing pin of hardened steel, the upper end 30 of which is of tapered form. The bearing pin 3 has a reduced lower end 9 which is threaded into the hub 8 of the spider 2, a shoulder 10 on the pin cooperating with the hub 8 of the spider to limit the downward movement of the pin 3 when the end 9 thereof is threaded into the hub 8. An annular foot piece 11 forms the intake for the casing of the pump and is held against the lower end of the base 12 by securing elements 14.

40 A cap 15 constitutes part of the casing, and is mounted upon the body 1, the cap 15 and the body 1 being shouldered together, as at 16, to prevent relative lateral movement between the parts specified. The cap 15 is held on the body 1 by securing members 17. The outlet for the body 1 is marked by the numeral 18 and is in the form of volute, formed integrally with the cap 15, and upstanding therefrom to minimize

space, considered horizontally. The outlet 18 communicates with the interior of the casing by way of a reduced throat 19, and the liquid, having traversed the outlet 18, flows away through an opening 18^a into a 60 nipple 20 formed integrally with the cap 15.

The cap 15 includes an upstanding tubular pedestal 21 surmounted by a gland 22, there being a bushing 23 in the pedestal 21, at a point near to the gland 22, the bushing 65 being preferably made of bronze.

Having thus described the casing or stator, the construction of the rotor will now be taken up.

A shaft 24 is journaled in the gland 22 70 and in the bushing 23 and has an axial passage 25 for the delivery of oil. The shaft 24 extends into the neck 26 of a rotor, the rotor including a body 27. The body 27 of the rotor is disposed between the cap 15 and 75 the body 1, the neck 26 of the rotor being located in the enlarged lower part of the pedestal 21. A thrust bearing 4, made of hardened steel, is seated in a recess 4^a in the neck 26 of the rotor, the thrust bearing being 80 shaped, as at 28, to receive the conical end 30 of the bearing pin 3. A key 29 holds the shaft 24, the thrust bearing 4 and the rotor together for simultaneous rotation, the key 29 being engaged with the neck 26 of the 85 rotor. The thrust bearing 4 has an oil port 38. This port communicates with the lower end of the oil passage 25 in the shaft 24. Oil introduced into the passage 25 will find its way, by means of the port 38, on the 90 conical end 30 of the bearing pin 3. The entire rotor is supported to turn on the conical end 30 of the bearing pin 4 and this part, it is to be observed, can be adequately lubricated, owing to the construction shown at 95 25—38. A bushing 31, generally of bronze, is located in the neck 26 of the rotor, about the bearing pin 3, and abuts against an internal shoulder 33 in the neck 26. The body 27 of the rotor has a central chamber 39 100 which receives the spider 2 and its hub 8. Passages 34, of which there may be any desired number, lead from the chamber 39 to the periphery of the body 27 of the rotor.

105 In practical operation, when the rotor is turned by means of the shaft 24, the liquid rises through the intake member 11 and moves upwardly through the spider 2, the liquid traversing the passages 34 of the rotor and moving upwardly into the outlet 110

member 18, by way of the throat 19, the liquid leaving through the opening 18^a and the nipple 20.

A ring 35 is located in a superficial annular recess 37 formed in the lower edge of the body 27 of the rotor, and the ring can play freely up and down, the ring having lugs 36 that are received in recesses 36^a in the lower part of the body 27 of the rotor. 5 As shown at 36^b, the ring 35 has a taper in cross section, so that anything that may happen to get behind the ring can work down and out. The ring 35 bears on another ring 40 which is seated in an annular 15 groove 40^a formed in the base 12 of the stator. When the rotor is in operation it forces liquid under pressure on top of the ring 35, and the ring is pressed down on the ring 40 so that there is no leak across the 20 extreme lower end of the body 27 of the rotor.

The bearing pin 3 is located entirely within the rotor, and the parts 6—7—8, which support the bearing pin, are located entirely 25 within the stator or casing. In this respect, the pump shown is different from pumps of that sort wherein the shaft that carries the rotor is journaled in a thrust bearing disposed outside of the casing. Such pumps 30 are hard to oil, and to maintain against the action of grit, whereas my pump is not.

What is claimed is:—

1. A pump comprising a stator having an inlet and an outlet, a rotor having a central chamber communicating with the inlet, the rotor being provided with laterally extended passages communicating with the chamber and discharging into the outlet, a substantially vertical bearing pin, means carried 35 by the stator and located in the chamber 40

for supporting the bearing pin, a shaft secured to the rotor, a thrust bearing seated in the rotor and interposed between the lower end of the shaft and the upper end of the bearing pin, the bearing pin and the 45 thrust bearing carrying the weight of the rotor, and means for lubricating the bearing pin through the shaft and the thrust bearing.

2. A pump comprising a stator having an 50 inlet and an outlet, a substantially horizontal rotor having a central chamber communicating with the inlet, the rotor being provided with laterally extended passages 55 communicating with the chamber and discharging into the outlet, a substantially vertical bearing pin, means carried by the stator and located in the chamber for supporting the bearing pin, and mechanism for supporting the rotor on the upper end of the bearing pin for turning movement and against downward movement longitudinally of the bearing pin.

3. A pump comprising a stator having an 60 inlet and an outlet, a substantially horizontal 65 rotor within the stator, the rotor communicating centrally with the inlet and having a lateral passage discharging into the outlet, a substantially vertical bearing 70 extending within the rotor, the bearing carrying the weight of the rotor and supporting the rotor against downward movement longitudinally of the bearing, and means mounted 75 on the stator, and housed completely within the stator, for supporting the bearing.

In testimony that I claim the foregoing as my own, I have hereto affixed my signature.

JAMES ANDREW GOODNER.
